UNITED STATES PATENT OFFICE.

WILLIAM F. HUTCHINSON, OF NEW YORK, N. Y.

LIGHTING CARS.

SPECIFICATION forming part of Letters Patent No. 554,697, dated February 18, 1896.

Application filed April 15, 1895. Serial No. 545,682. (No model.)

To all whom it may concern:

Be it known that I, WILLIAM F. HUTCHINSON, of the city, county, and State of New York, have invented certain new and useful 5 Improvements in Lighting Cars, of which the following is a full, clear, and exact description.

My invention relates to improvements in lighting cars, and particularly such cars as 10 are propelled by a moving source of power, such as a screw along the track.

It is desirable to light cars by electricity; but it is difficult under most circumstances, because it is a hard matter to keep the dynamo 15 running at a desirable rate of speed during the time that the car is running and also when the car is stationary.

The objects of my invention are to produce a simple and convenient means of running an 20 electric generator, such as a dynamo, from the source of power which propels the car and to arrange the apparatus so that the dynamo can be constantly run whether the car is in motion or not; also to arrange and support 25 the dynamo and its driving mechanism in such a manner that the driving mechanism will not be affected by the rise and fall of the car-floor, due to the varying load of the car.

To these ends my invention consists of an 30 apparatus for lighting cars, which will be hereinafter described and claimed.

Reference is to be had to the accompanying drawings, forming a part of this specification, in which similar figures of reference indicate 35 corresponding parts in all the views.

Figure 1 is a broken longitudinal section of the car provided with my improved apparatus, the latter being shown in elevation. Fig. 2 is a vertical cross-section on the line 2 2 of 40 Fig. 1, and Fig. 3 is a broken plan view of the lighting apparatus.

My invention is particularly well adapted for use in connection with the railway for which I secured Letters Patent of the United 45 States No. 538,784, dated May 7, 1895, although I do not confine my invention to use in connection with such special construction as the said patent shows.

As illustrated, the car 10 is mounted on the 50 usual wheels 11 to run on the ordinary track-rails 12, and beneath the car-floor and journaled on the axle of the car is a frame 13,

which supports a carriage 14, the latter carrying a gear mechanism 15, which connects with and is driven by a revoluble screw 16, 55 which extends along the track. The gear mechanism 15 drives a vertical shaft 17, which by means of beveled gear-wheels 18 and 19 imparts motion to a shaft 20 on the frame 13, and the latter shaft by means of the beveled 60 gear-wheels 21, 22 and 23 drives the counter-shaft 24, which is journaled on the frame 13, and which connects by means of the clutch-controlled gear-wheel 25 with a gear-wheel 26 on one of the axles 27 of the car. 65

I have shown and described the foregoing mechanism in a general way only for the reason that it is like the mechanism in my former patent, referred to above, the only difference being that in the present case but one 70 clutch-controlled gear-wheel 25 is shown, whereas in practice a series of gear-wheels are used to connect the counter-shaft and axle, as illustrated in my former patent, in order that a differential speed may be obtained. 75

The gearing between the wheels 15 and 11 is such as to cause a differential action—that is to say, if the screw were supposed to be stationary and the car to be slid along a forward motion of fifty-one inches in the wheel 11 would produce a forward motion of, say, fifty inches at the circumference of the wheel 15, the difference of one inch being taken up by the rotation of the screw—that is, a rotation of the screw at moderate speed produces a high velocity of translation for the car, and consequently a high speed for the dynamo when the latter is in gear, as hereinafter described. 90

On the frame 13 is supported a second frame 28, which projects upward through the car-floor, as shown clearly in Figs. 1 and 2, and this frame 28 carries an electric generator or dynamo 29, which may be of any usual kind, 85 and which has on the armature-shaft 30 a gear-wheel 31, which is controlled by any customary form of clutch, worked by a lever 32. 95

The gear-wheel 31 connects by means of meshing gears 33 and 34 with a driving-gear 35 on the counter-shaft 24, and as the counter-shaft is constantly driven by means of its gear connection with the screw 16, already described, it will be noticed that the dynamo 100

will also be constantly driven unless it is thrown out of gear by the lever 32, and so the dynamo will operate equally well whether or not the car is in motion.

5 It will be understood that other forms of gearing may be used to drive the dynamo from the screw without departing from the principle of my invention, and that, if desired, a train of gearing wholly independent 10 of anything used to propel the car may be utilized. The dynamo may also be supported directly on the car-floor; but it is better to support it independently of the floor, so that the dynamo will not be affected by the rise and 15 fall of the floor, and can, therefore, be driven without any derangement of the gearing.

The screw-and-gear mechanism described makes a very positive means of driving the dynamo, and by the use of this mechanism 20 the car may be constantly lighted and the lights will not vary by the variation in speed 25 of the car, as the speed of the screw is con-

stant, and the connection between the screw and dynamo is a positive connection.

Having thus described my invention, I 25 claim as new and desire to secure by Letters Patent—

1. The combination with the car and the revoluble screw on the car-track, of the generator on the car, and a train of gearing connecting the generator with the screw, substantially as described. 30

2. The combination with the car and the revoluble screw along the track, of the gear mechanism arranged to travel along and be 35 driven by the screw, and an operative driving connection between the said gear mechanism and the generator, substantially as described.

WILLIAM F. HUTCHINSON.
